UNITED STATES PATENT OFFICE

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY

LASTING OF SHOES

Application filed July 23, 1923, Serial No. 653,291. Renewed November 27, 1928.

This invention relates to shoemaking, and in many of its important aspects more particularly to the lasting of shoes. The invention has important advantages in its application to the manufacture of welt shoes, where the upper is fastened to a lip or rib on the insole, and of McKay shoes, for example of that type where the insole is provided with an upper-attaching lip, and accordingly it is herein illustrated as applied to the manufacture of these two kinds of shoes. In various aspects, however, the invention presents advantages also as applied to the manufacture of other kinds of shoes, for example turn shoes where the upper is fastened to a shoulder on the sole. The term "sole" is therefore frequently used hereinafter in a generic sense as applicable to the insole of a welt, McKay or other doubled soled shoe, or to the sole of a single soled shoe such as a turn shoe.

In lasting the sides of welt shoes and of McKay shoes of the type above mentioned it is the common practice to fasten the uppers in lasted position by means of temporary fastenings, usually lasting tacks, driven at frequent intervals along the sides of the shoes. It would, however, be a matter of great difficulty, if not practically impossible, to sew 25 welt shoes with these lasting tacks remaining in position, due to the difficulty of avoiding the tacks and the danger of breaking the needle, and in McKay shoes the tacks of course must be removed before the outsole is applied. It is accordingly the usual practice to return the shoes to the racks for a number of hours, and it may be for a day or more, until the uppers have become substantially 35 set in lasted shape, and then to insert staples 40 through the upper and the lip of the insole to assist in holding the upper for sewing, thereafter removing the lasting tacks.

There are many recognized objections to the practice above outlined, prominent among 45 which are the expense involved in maintaining a large supply of lasts and in providing racks sufficient to hold the shoes while the uppers are becoming set in lasted shape, and the need for floor space sufficient for such 50 storing of the shoes, as well as the waste of

time involved in the manufacture of any particular shoes in waiting for the uppers to set. There is also added expense in the necessity for repeated handling of the shoes. Moreover, where the practice is followed of 55 stapling the upper to the insole to permit the removal of the lasting tacks it is a matter of considerable difficulty, due in large part to the presence of the tacks, to insert the staples in the best locations and with such degree of accuracy as to insure that they will hold the upper in the most satisfactory manner for the sewing operation. It is found, therefore, that under the usual factory conditions these 60 staple fastenings vary greatly in their effectiveness, and that the manner in which the upper is thus held not infrequently has an unfavorable effect upon the character of 65 subsequent operations in the manufacture of the shoe. On the other hand, if the lasting 70 tacks are removed one by one as the staples are driven, to make way for the staples, as is sometimes the practice, there is danger of displacement of the upper from properly lasted position. In turn work comparatively few 75 lasting tacks are needed along the sides of the shoe, and accordingly it is the usual practice to sew these shoes while the lasting tacks are present, although to a certain extent their 80 presence involves the same difficulties as in welt work.

In view of these and other considerations, the present invention, in one of its important aspects, has in view the lasting of shoes, or portions of shoes, without the use of temporary fastenings which must be subsequently removed, and the invention accordingly provides a novel machine organization designed to work the upper into lasted position and to fasten it to the sole by the use of fastenings, herein shown as staples, that may remain permanently in the shoe, and further provides a novel method for securing improved results by the use of such fastenings. A still further object is to improve in general 95 the character of the lasting, irrespective of the manner in which the upper is fastened in lasted position. For the accomplishment, in general, of the objects in view, the invention, in one of its important aspects, 100

provides a novel method of working the upper into lasted position and a novel organization of means for carrying out the method. In accordance with the practice herein illustrated, the upper is pulled to tension it relatively to the last and the sole, and is then forced over the margin of the sole, and as herein shown inwardly into the angle between the margin or feather and the lip or shoulder of the sole, by engaging it in a location spaced a substantial distance from the edge of the sole and spaced also initially from the plane of the sole with pressure directed inwardly at a substantial inclination to the plane of the sole. Preferably the upper will be held under more or less pulling tension while it is thus forced inwardly into lasted position, and it may be until the upper is fastened in lasted position. In this way the upper is wrapped about the edge of the sole and is bent over its outer face or tucked into the angle between the feather and the lip or shoulder of the sole in a very tight and effective manner, without danger of displacing the marginal edge or feather of the sole in the overlaying operation. An important factor in the tightening effect on the upper in thus laying it over the sole is the application thereto of pressure substantially localized at a distance from the edge of the sole, as above described, since there is thus a minimum amount of friction between the upper and the margin of the sole tending to resist the pull on the upper resulting from the bending action thereon. It is further contemplated that the best results in carrying out these operations on the shoe will be secured by adjusting the force of the pull of the gripper on the upper to the overlaying pressure as the upper is laid inwardly over the margin of the sole, in order to avoid excessive strain on the upper, and in this as well as its many other aspects the invention presents novelty both in the method and in the machine organization. Still further to assist in avoiding displacement of the margin of the sole and in stretching the upper tightly over the last, it is preferred that the upper be pulled first in a direction inclined outwardly from the edge of the sole, as herein illustrated.

In one of its important novel aspects the invention has in view the fastening of the upper to the lip or shoulder of the sole by fastenings inserted in directions inclined to the plane of the sole, so that the inner ends of the fastenings will be located, for example, close to the base of the lip of the sole, or to the base of the channel where the sole is channeled to form the lip. Among other advantages, this serves substantially to avoid danger that the lip may be pulled outwardly by the tension of the upper before the upper has become set in lasted shape. A very effective and simple arrangement of means for laying the upper inwardly into lasted position by

pressure applied in a direction inclined to the plane of the sole, as hereinbefore described, and for inserting fastenings in directions inclined to the plane of the sole comprises an arrangement such as herein illustrated, including an overlaying member movable at the required inclination to the plane of the sole and constructed to serve as a guide for fastenings which are driven at substantially the same inclination to the sole to fasten the upper to the lip. 75

In addition to features which are generally advantageous as applied to the manufacture of welt, McKay and other kinds of shoes, the invention further provides an organization which has special advantages in operating upon McKay shoes of that type in which the insole is provided with an upper-attaching lip. Such a lip is customarily formed by channeling the insole outwardly toward its edge, so that the lip tends to incline inwardly away from the edge. It is, moreover, desirable that in the fastening of the upper to the lip the latter be thus inclined more or less inwardly, in order that the upper may not oppose undue resistance to the subsequent return of the lip to a position flat upon the insole. The machine herein shown, as equipped for operating upon McKay shoe work, is provided with means for thus positioning the lip in inclined relation to the plane of the insole, and the arrangement is also such that the fastenings, driven in directions inclined to the plane of the insole as hereinbefore explained, enter the inclined lip in directions substantially perpendicular to the lip. This affords further insurance that the fastenings will be properly driven through the lip and clinched and that the upper will be fastened tightly to the lip. 100

It is furthermore within the province of the present invention to subject different portions of the upper, if desired, to different treatment. It is contemplated by the present invention that where conditions render it desirable and feasible to do so, the upper will be brought into lasted position and fastened at comparatively wide intervals, and thereafter the intermediate portions of the upper also will be brought into lasted position and fastened by a different treatment. As herein illustrated, for example, the upper may be subjected at comparatively wide intervals to an updrawing and an overdrawing pull, and thereafter the intermediate portions of the upper may be subjected to an overdrawing pull only, the machine herein shown being provided with means whereby the updrawing pull of the gripper may be conveniently eliminated. This permits the use of a more strongly tensioned updraw spring than heretofore without danger of loosening previously inserted fastenings. It is also contemplated that on a considerable portion of the shoe, for example in the inside shank portion where 110

less updraw pull is required and where a hard pull may result in serious distortion of the upper, the updrawing pull may be omitted in operating upon different successive portions of the upper.

In lasting the sides of shoes it is particularly difficult to treat in an effective and satisfactory manner portions of the upper in the locations where the edge of the sole and the sides of the last curve inwardly at the rear of the ball line. In these locations the upper requires a substantially hard pull to stretch it properly over the instep and to conform it to the inwardly receding curvature of the last and the edge of the sole, and by preliminarily pulling the upper properly and fastening it in these locations in operating on some kinds of work the lasting of the remaining portions at the sides of the shoe may be facilitated. In order that the upper may be pulled in these locations with the required degree of force without danger of distorting it, there are advantages in applying the pull at the opposite sides of the shoe simultaneously, and a machine by the use of which shoes may be subjected to such treatment and the upper fastened by tacks in the locations mentioned prior to the usual progressive side lasting operation is shown and described in a prior application of Bernhardt Jorgensen, Serial No. 626,083, filed on March 19, 1923. It is contemplated that under some conditions it will be advantageous that shoes in which the upper is fastened in the lasting operation in the manner herein illustrated to the lip or shoulder of the sole be subjected to such preliminary treatment at the points above referred to, in order that the lip of the sole, for example, may not be subjected to an excessive degree of outward pull or that the lasting fastenings may not be loosened through the tension of the upper after the lasting operation. In one aspect, therefore, of the present invention I contemplate pulling simultaneously and fastening portions of the upper at the opposite sides of the shoe in the locations where the edge of the sole curves inwardly toward the shank, thus taking the stretch out of the upper at these points prior to the side lasting of portions forwardly of the ball line and in the shank, and thereafter lasting the sides of the shoe progressively by working the upper along the sides inwardly and fastening it to the lip or shoulder of the sole.

In still another aspect the invention presents features of novelty in the general organization and arrangement of the operating instrumentalities whereby ample room is afforded for the manipulation of the work in the proper manner and for the movements of the different instrumentalities to perform their required functions. The machine herein shown has means for forming the upper fastening staples, and it is one advantageous

feature that in combination with the upper-tensioning means there is provided means whereby the staples are formed in a plane located at a substantial distance from the plane in which they are driven, the machine shown comprising a staple forming member having a movement to transfer the staple to the driving plane.

The above and other features of the invention, including various details of construction and combinations of parts, and the method in its various novel aspects, will now be more particularly described by reference to the accompanying drawings and pointed out in the claims.

In the drawings,

Fig. 1 is a view in side elevation of a portion of the head of a lasting machine adapted for use in practicing the novel method and illustrating one embodiment of the novel features of the invention;

Fig. 1^a is a detail view, largely diagrammatic, illustrating the closing of the gripper jaws;

Fig. 2 is a side elevation of the head of the machine looking at the side opposite to that shown in Fig. 1;

Fig. 3 is a front view of the machine with parts of the gripper mechanism removed to show the fastening forming and inserting mechanism;

Fig. 4 is a view in perspective and partly in section of parts of the fastening forming and inserting mechanism;

Fig. 5 is a detail view of the fastening forming devices with the wire fed in position to be severed to form the fastening;

Fig. 6 shows the same parts as Fig. 5 with the wire about to be cut;

Fig. 7 is a view similar to Figs. 5 and 6 in which the outside former has descended to place the formed fastening in front of the driver;

Figs. 8, 9 and 10 are sectional views which illustrate steps in the formation of the staple fastening;

Fig. 11 shows in perspective one side of the outside former;

Figs. 12, 13, 14 and 15 show successive steps in the lasting operations on a welt shoe;

Figs. 16, 17 and 18 illustrate similar steps in the lasting of a certain type of McKay shoe;

Fig. 19 shows a portion of a lasted welt shoe;

Fig. 20 is a similar view of a lasted McKay shoe;

Fig. 21 illustrates a step in the process of lasting a shoe along the shank portion thereof; and

Fig. 22 shows the bottom of a shoe after the upper has been pulled over and fastened on both sides near the ball line of the sole.

In the machine shown the lasting means comprises a gripper having a pair of jaws

of which the lower one 30 is fixedly secured, as at 32, to the lower end of a bracket member 34 of a sleeve member 36 mounted for vertical sliding movement in a bearing 38 which is mounted to rock about a pivot 37 in the forward end of a horizontally movable slide 40. The other jaw 42 is connected to the lower end of a rod 44, inside of the sleeve 36, by means of a short link 46, the body portion of the jaw 42 being also connected by a pivoted link 48 with the bracket member 34 which carries the jaw 30. It will be understood that reciprocation of the rod 44 will cause movement of the jaw 42 in directions toward and from its cooperating jaw 30 to seize and release a portion of the upper of a shoe interposed between the serrated ends of the jaws. Both jaws are moved together in an upward direction to effect the updraw movement by which the upper is pulled upwardly to tension it on the last. To cause the updraw movement just described, the upper end of the sleeve 36 is connected, by a ball and socket joint indicated at 50, to the forward end of a lever 54 pivoted at 56 (Figs. 1 and 2) on the frame or head 58 of the machine. For rocking the lever 54 there is connected to its rear end a slide 62, the slide having a reduced rod part 64 which passes slidably through a block (not shown) pivoted at 60 in the lever 54, said slide carrying at its lower end a pin and roll 66, the roll being mounted in a cam groove 68 in a cam wheel 70 arranged to be clutched, as hereinafter more fully described, to a shaft 71, which is the driving shaft adapted to be controlled from connections 73 leading to a treadle (not shown). Upon rotation of the cam wheel 70 the slide 62 and connected rod 64 are reciprocated and during downward movement thereof apply yielding pressure through a spring 72 upon the rear end of the lever 54, thus effecting a yielding, updraw movement of the gripper at the front end of the lever. Extending through the sleeve 36, as before mentioned, is the rod 44, the upper end of which also passes through the ball member of the ball and socket joint 50 so that the upper end of said rod may be engaged to force the rod downwardly, thus closing the gripper. For thus forcing the rod 44 downwardly there is provided a shaft 80 (Figs. 1 and 2) mounted rotatably in a bearing 82 carried by the forward end of the lever 54 and a second bearing 83 in the end of the rotatable pivot 56 upon which the lever 54 oscillates. Fixed to the rear end of the shaft 80 is an arm 84 carrying at its lower end a roll 86 adapted to contact with the periphery of a cam wheel 88 fixed on the shaft 71, whereby the arm 84 and shaft 80 are rocked about the horizontal axis of the shaft. Secured to the other end of the shaft 80 is another arm 90 having a spring-controlled plunger therein provided with a socket 92 (Fig. 2) to receive the upper end of the rod 44. For re-

turning the rod 44 upwardly after a depression thereof there is provided a spring 100 surrounding the sleeve 36 and resting at its lower end upon the upper end of the bearing 38, its upper end pressing against a washer 102 slidable on the sleeve 36 and connected to transmit upward movement to the rod 44 by a pin 104 fixedly secured to the rod 44 and extending through a slot 106 in the sleeve 36. Clamped to the sleeve 36 is a collar 108 which is adjustable on the sleeve to vary the position of the pin 104 when at its upper position of rest, thus setting a limit to the upward movement of the rod 44 and of the upper gripper jaw 42 relatively to the sleeve 36. 70 75 80

As before stated the sleeve 36 is slidably mounted in the bearing 38 at the forward end of the slide 40. For reciprocating the slide 40 the latter is provided between its ends with a stud carrying a roll 112 (Fig. 2) the said roll being held yieldingly against a face cam 114 on the cam wheel 88 by a spring pressed lever 118 which engages the end of the slide, there being a washer of hardened fibre 120 between a head on the end of the slide and a portion of the frame to limit movement of the slide. For tensioning the spring which operates the lever 118 in one direction there is provided a hand lever 122, a pawl 124 and a ratchet wheel 126, all of which operate in a common and well known manner. It will be understood that upon rotation of the shaft 71, to which the cam wheel 88 is fastened, the slide 40 will be moved to the right in Fig. 2, at which time the gripper jaws 30, 42 are open in a position to seize the edge of the upper of the shoe, this movement of the slide being caused by the high portion of the cam 114. Continued rotation of the cam brings the roll to the low portion thereof, to cause the slide 40 to be actuated by the spring pressed lever 118, as before described, so that the movement of the slide 40 toward the left in Fig. 2 is produced yieldingly and the closed gripper jaws 30, 42 are given their overdraw movement to pull the edge of the upper inwardly over the edge of the last. For a more detailed description of the means thus far described for causing the closing of the gripper and for effecting the updraw and overdraw movements of the gripper reference may be had to Patent No. 584,744 granted June 15, 1897 upon application of S. W. Ladd and R. F. McFeely. Means is preferably provided for varying the tension of the spring 72, the said means comprising a sliding wedge 130 (Fig. 2) having a plurality of seats 132 for a pin 134 in a block 136 slidable on the lower end of the rod 64, the arrangement being such that movement of the wedge 130 toward the left in Fig. 2 will raise the block 136 to compress the spring, thereby exerting greater pressure upon the rear end of the updraw lever 54 which will be manifested during the updraw movement of the gripper. 95 100 105 110 115 120 125 130

For operating the wedge 130 there is connected thereto a rod 138, the forward end of which carries a handle 140 in a position accessible to the operator so that the wedge may be adjusted as desired. This adjustment mechanism for varying the force of the pull on the upper is shown in detail in Patent No. 893,331 granted July 14, 1908 on application of S. W. Ladd.

10 Means is provided for operating the gripper in such a manner as to insure as far as possible that the marginal portion of the upper will be properly seized by the gripper jaws in the movement which precedes the upper draw and overdraw movements of the gripper. In the present construction novel means is provided whereby the movable jaw is caused to occupy a position widely spaced with respect to the relatively stationary jaw 20 in the first portion of its closing movement. Hence the movable jaw moves into such close juxtaposition with respect to the nose 212 of the fastening inserting means as to insure that the margin of the upper will be properly 25 embraced by the jaws. Subsequently the jaws are closed by movement of the movable jaw directly toward the stationary jaw, whereby the upper is securely gripped. Failure to grip the shoe upper is thus practically 30 eliminated except as other factors, such for instance as a scant upper or negligence on the part of the operator, may affect the proper operation of the gripper. Referring to Figs. 1 and 1^a of the drawings, it will be seen that 35 the bracket member 34 is provided with a cam member 142 having a cam projection 144 which is adapted to engage with an intermediate convex portion of the cam surface 146 on the movable gripper member 42 when the jaws 40 are in starting position. After the gripper jaws 30 and 42 move toward the left in Fig. 1 the jaw 42 is moved downwardly relatively to the jaw 30 to bring a concave cam portion 148 opposite the cam projection 144 so 45 that the lower end of the jaw 42 moves further to the left when it get below a block 324, hereinafter referred to as indicated in Fig. 1^a, thus opening the gripper jaws practically to their extreme extent at the very beginning 50 of the downward movement of the closing rod 44. Near the end of the downward movement of the closing rod the cam projection 149 at the extreme upper end of the movable jaw 42 is engaged with the cam projection 144, whereby the lower end of the jaw 42 is caused to move sharply into gripping relation to the end of the gripper jaw 30. For 55 separating the jaws at the end of their upward movement and for holding them in 60 open position, there is provided a spring pressed plunger 151 (Fig. 1) which operates similarly to the disclosure of Patent No. 1,005,234, granted Oct. 10, 1911 on an application of S. W. Ladd and E. A. Stiggins, for 65 improvements in grippers for lasting ma-

chines. In the construction herein shown the cam member 142 is concaved to such an extent that the cam projection 149 never contacts with the member 142 until it reaches the projection 144 thereon, although the link 46 and the projection 149 are held over toward the member 142 under the constant pressure of the spring pressed plunger 151. It will be understood that the link 48 assists in the opening and over-reaching movement of the upper jaw just as in the prior construction of the cited Patent No. 1,005,234. Novel features of this gripper are claimed in Letters Patent No. 1,712,611 granted on May 14, 1929 upon an application filed as a division of the present application.

70 Preferably and as shown, the fastening inserting means is of the type which makes and drives staple fastenings. In order that ample space may be provided for the introduction and manipulation of the work and for the proper operation of the gripper, the fastening forming and inserting mechanism is specially constructed to form the staple in one plane and subsequently transfer it to the 75 plane of the driver element. Moreover, the fastening forming and driving devices are, for the most part, so mounted as to be retractile and projectile with respect to a stationary work rest 150 which is fixedly carried by a bracket 152 on the head or top frame 58 of the machine. The said work rest 150 is a curved member, as most clearly shown in Fig. 3 of the drawings, having its end portion provided with an anvil formed with clinching cavities 153 (Fig. 6) designed to turn the ends of the staple legs or prongs directly outwardly with respect to each other. It is considered an important feature that the work rest 150 is a stationary member 80 since it enables the operator to position his work with greater accuracy and rapidity than is possible with a movable work rest. Moreover, the stationary work rest forms a backing against which the gripper is highly effective in its pull to updraw the upper of the shoe and to overdraw the said upper in tensioning it about the last and carrying its marginal portion over the insole which is at the same time held firmly in contact with the 85 last thus securing a snug fit of the upper to the last. Furthermore, the work is accurately positioned and retained against movement during the overlaying operation effected by the forward movement of the overlaying element at the forward end of the fastening inserting means, as will be hereinafter more 90 particularly described.

95 In the illustrative fastening forming and inserting means, there is provided an inside former 160 (Fig. 4) supported in a stationary bracket 162 fixedly secured to the top frame 58 of the machine, the inside former being carried by a shank part 164 secured for 100 adjustment by a set screw, as indicated at 105

166. All of the rest of the staple forming and guiding devices (excepting the stationary cutter) are carried at the forward end of a reciprocable slide 170 (Figs. 1 and 2). For 5 reciprocating the slide 170 in an inclined guideway 173 in the frame 58, there is provided a lever 175 having an adjustable fulcrum at 177 on the frame and a roll at its upper end for engagement in the cam groove 10 179, the lower end of the lever being connected yieldingly to a link 181 pivoted at 183 to the slide 170. It will be understood that the slide is operated in timed relation to the gripper mechanism and to the operations of 15 the fastening forming and driving devices carried by the slide. As shown, the outside former 171 (Fig. 5) comprises two plates 172, 174 secured to a slide bar 176 which is reciprocated to carry the staple from forming position to driving position, as will be 20 hereinafter described, the staple forming movement taking place as the slide 170 moves toward the work rest 150. Also carried by the slide 170 is a cutter 180 adapted to shear 25 the wire *w* in cooperation with a fixed cutter 182 carried by the stationary bracket 162. In order that the wire *w* may be properly guided across the end of the inside former 160 there is provided a pair of slotted side guide members 30 184 which support the wire while the end thereof extends across the space closely adjacent to the end of the inside former, the extreme end of the wire being in contact with an adjustable abutment 186 carried by 35 the fixed bracket 162. The guide members 184 are carried at the extreme forward end of the staple guiding and driving devices so that upon forward movement of the slide 170 they move one along each side of the inside former 160 until just before they pass 40 from the wire the cutters operate to sever it and at the same time the outside former members 172, 174 engage the wire as indicated in Fig. 9, to press it against the face of the 45 inside former. By continued movement the outside former forms a U-shaped staple, as most clearly indicated in Fig. 10 of the drawings. Just at the completion of the forming movement of the outside former, the 50 cross-bar of the staple is engaged by a die member 190 at the lower end of a plate 192 fixed to the forward face of the casing 193 which forms a housing for the bar 176, the die operating in the space between the outside 55 former members 172, 174 to engage the cross-bar of the staple to make a straight cross-bar in cooperation with the face or end of the inside former 160. This is a relatively important feature of the fastening forming 60 mechanism since in view of the provision of the die 190 it is possible to bend the legs of the staple about the inside former without exerting such a drawing tension on the legs of the staple as would otherwise be needed 65 to make an approximately straight cross-bar.

Because of the use of the die 190 the outside former does not need to draw tightly on the wire to make the cross-bar, since the die performs this operation in conjunction with the inside former, and hence there is no danger of weakening the staple at the junction of the legs and the cross-bar and a better and stronger staple is provided. If desired the die and operative face of the inside former may be shaped to give a curved contour to 70 the cross-bar of the staple fastening. 75

At the end of the forward movement of the slide 170 the staple is fully formed, as indicated in Fig. 10. By the time that the staple is fully formed the rear edge of a 80 staple controller member 198 (Fig. 7) which moves with the outside former, is in alinement with the operative face of the inside former 160. Hence, as the outside former moves downwardly, to transport the staple to the driving plane, the staple is caused to straddle the controller member 198, the latter thereby maintaining the staple properly within grooves 200 (Fig. 11) in the outside staple forming members 172, 174, the 85 said grooves receiving the staple legs at the time of formation of the staple. In order to insure that the cross-bar of the staple will not catch upon the upper edge of the controller member 198 in passing downwardly 90 from the end of the inside former 160, the upper corner of the controller member is beveled off, as indicated at 202. At the end of the downward movement of the outside former the staple is located below the lower 95 end of the staple controller member 198 and in the path of a staple driver 204 (Fig. 7), the arrangement being such that the lower end of the outside staple former 171 embraces a bed member 206 of the driver guideway. 100 The result of this arrangement is that the staple legs are confined in a space between the bed member 206 below and shoulders 208 (Fig. 11) which define the upper walls of the grooves 200 in the former members 172, 174, in which the staple was originally formed. Furthermore, the driver bar 204 is guided in the same way as the staple itself, that is, between the guide bed 206 and the shoulders 208 on the former members 110 172, 174 and in the grooves 200. It will be understood that the guideway thus formed is in alinement with the driver guideway 210 in the staple guiding nose 212 from which the staple is driven into the work. As will be hereinafter pointed out the nose 212 also 115 functions as an overlaying member in the lasting operations. Since the outside former members 172, 174 must be brought accurately into proper alinement with the wire guides 184 at the upper limit of the movement of the outside former 171 and must also be accurately fitted with relation to the bed 206 so as to bring the staple into the plane 120 of the driver and yet not pinch the staple 125 130

or the driver against the bed, means is provided for fixing the limits of the up and down movements of the outside former 171 by set screws 214, 216 adapted to engage a stud 218 projecting from the slide bar 176, the said set screws 214, 216 being adjustably clamped in position so that adjustment may be made in setting up the machine and in accommodating the parts to any wear that may take place.

For moving the outside former 171 from staple forming to staple delivering position, as above described, there are provided operative connections from a cam wheel 220 (Fig. 15) fixed on the shaft 71, the said connections comprising a lever 222 pivotally mounted on a pivot 224 fixedly secured in the head frame 58 and having a roll 226 to engage with the cam wheel 220. At its other end the lever 222 is pivotally connected to a link 228 upon which is slidably mounted a sleeve 230, a spring 232 being interposed between the upper end of the sleeve 230 and the end of the lever 222. As shown, the sleeve 230 is screw-threaded exteriorly, thus providing for adjustment of a hub 234 which surrounds the sleeve and is adjusted upon turning the sleeve, as will be readily understood from inspection of the drawings, and more particularly of Fig. 1. Connected to the hub 234 is a rod 236, the lower end of which is pivotally connected to a projecting arm 238 (Fig. 4) secured to or integral with the former bar 176. For yieldingly maintaining the roll 226 in contact with the cam wheel 220 there is provided a spring 240 (Figs. 2 and 3) secured on the fixed pivot 224 of the lever 222, one end of the spring being connected to the pivot 224 and the other end engaging with a pin 242 on the side of the lever 222 so as yieldingly to maintain the lever in contact with its operating cam. From a consideration of the construction just described, it will be clear that the former bar 176 is yieldingly actuated in both its upward and downward movements so that the set screws 214, 216 are permitted to determine the positions of rest of the outside former 171 in its staple forming and staple delivering positions.

After the staple has been formed and delivered by the outside former 171, it is driven into the work by the staple driver 204, as above described. The means for operating the driver bar comprises preferably a spring 55 which is wound up and then tripped at the proper instant to effect a practically instantaneous staple inserting operation. In the illustrated construction there is pivoted upon an extension from the slide 170 on a pivot bar 248 a driver operating lever 250 having its lower end bifurcated, as at 252 (Fig. 1), to hold adjustably clamped therein a bar 254 having its lower end swiveled in a block 256 slidably mounted in a driver bar 258 to which 65 is fixedly secured the staple driver 204.

Wound around the pivot 248 is a spring 260 (Fig. 4) having one end 261 caught under a shoulder on the lever 250 and its other end secured to a part of the supporting extension of the slide 170, the said spring being relatively heavy and adapted to operate the lever 250 forcibly to effect the operative stroke of the staple driver. For turning the lever 250 against the tension of the spring 260 there is provided a depressing means for the outer end of the upper arm of the lever 250, which means is adapted to be tripped at the proper time to permit the operation of the spring 260. In the illustrated construction, this depressing means comprises a link 264 (Figs. 1 and 2) pivotally connected at 266 to a slide 268 which is vertically reciprocated by being rigidly connected with a crank operated slide 239 at the front end of the shaft 71. Wound upon the pivot 266 of the link 264 is a spring 270 (Figs. 2 and 3) adapted to move the link 264 yieldingly toward the front of the machine so that its lower end will be pressed into position to engage a shoulder 276 formed on a plate 272 on the link (Fig. 1) with the upper edge of a similar plate 274 carried by the front end of the lever 250. This engagement of the shoulder 276 on the plate 272 with the upper end of the plate 274 takes place after the upward movement of the link 264, the result being that the lever 250 is turned in a clockwise direction to wind up the spring 260 on downward movement of the link 264, the lower end of the rear arm of the lever 250 moving rearwardly to retract the staple driver 204 from the path of the staple which is brought down by the outside former 171. This tensioning of the spring 260 and the retraction of the staple driver 204 take place at or near the end of the forward movement of the slide 170; and after the slide has completed its forward movement and the staple has been transferred, a cam block 280 adjustably fixed to the front side of the link 264 engages with a cam surface 282 carried by an arm 284 fixed to a stationary part of the head frame 58, the result of the engagement of the parts 280, 282 being to trip the link 264, causing disconnection of the shoulders on the plates 272, 274 so that the driver lever 250 is released with the result that the spring 260 immediately operates to shoot the staple driver forwardly to insert a fastening into the work. Carried by the slide 170 is a projection 290 in which is mounted by screw threads a button 292 which may be adjusted by turning the same with the aid of a screw driver having its end inserted in the slot 294, the rear end of the button 292 preferably carrying a disk of hard fibre 296 which acts as a buffer against which a boss 298 on the lower arm of the driving lever 250 may strike at the termination of the driving movement of the lever.

The wire from which the fastenings are formed is carried upon a reel 300 (Fig. 3)

from which it is fed through the operation of wire feeding rolls 302, 304, the latter being yieldingly pressed against the former by spring means indicated at 305, Fig. 1. For 5 operating the feed rolls there is provided a pawl and ratchet mechanism 306, 308 (Fig. 1) arranged to receive intermittent driving movement from a rocking arm 310 yieldingly backed by a spring 312 on a shaft 314 which 10 is rocked through the operation of a cam at the lower end of the vertical shaft 316 which is driven through intermeshing gears 318, 320, the latter being fixedly secured to the shaft 71. The wire feed mechanism is thus 15 briefly described since it forms no part of the invention. Any other well known wire feeding mechanism may be substituted therefor provided it is adjustable and can be made to feed the wire intermittently in definite 20 amounts to the staple forming and driving mechanism. After the wire leaves the feed rolls 302, 304 it passes through a wire guiding tube 322 (Figs. 1 and 4) by which the wire is directed to a guide block 324 fixedly 25 secured to the bracket 162 which is stationary with the head frame of the machine. From the wire guiding block 324 the wire passes into the slot of the adjacent movable guide blocks 184 and just to the rear of the station- 30 ary cutting block 182, the adjustment of the throw of the feed rolls being such as to carry the wire across the space at the rear face of the inside former 160 and into contact with the adjustable abutment 186. The end of the 35 wire is thus in position to be cut off through the operation of the movable and stationary cutters 180, 182, as before described.

Novel features of the staple forming, transferring and driving means are claimed in a 40 divisional application, Serial No. 198,180, filed on June 11, 1927.

When the machine, as thus far described, is thrown into operation by depressing the usual treadle, not shown, the gripper jaws 30, 45 42 are operated to seize the upper on the last, draw it upwardly by an updraw movement, then inwardly over the edge of the insole on the last in an overdraw movement, and finally 50 to move downwardly to facilitate the overlaying of the upper as the nose 212 moves inwardly over the edge of the sole in its overlaying operation on the upper. Under certain circumstances it is desirable, as already 55 stated, that the updraw movement of the gripper should be discontinued while the mechanisms which cause the overdraw and the closing and opening movements of the gripper jaws are continued in action. As stated in the foregoing description the updraw lever 60 54 for the gripper is operated from a cam wheel 70 (Fig. 2) adapted to be clutched to and unclutched from the shaft 71. So long as the cam wheel 70 is clutched to the 65 shaft 71 the updraw lever 54 will be

operated and the gripper will, of course, have its regular updraw movement in timed relation to its other movements. When the operator desires to discontinue the updraw movement, he makes use of mechanism 70 provided for the purpose of unclutching the cam wheel 70 from the shaft 71. In the illustrative construction, this mechanism comprises a shaft 340 (Fig. 2) mounted in bearings in the head frame 58 and carrying at one end fixedly secured thereto an arm 342 having a cam or wedge portion 344 adapted to engage with a shoulder on a pin 346 to withdraw the latter from a recess 348 in a member 350 fixed on the shaft 71. When this occurs the cam wheel 70 no longer turns with the power shaft and the updraw lever 54 remains stationary. For rocking the shaft 340 to move the wedge or cam 344 into or out of operative position, there is connected to the shaft 340 at its other end an arm 352 (Fig. 3) the outer end of which is perforated to receive a rod 354. Above the perforated end of the arm 352 the rod 354 is surrounded by a spring 356 which extends from the upper 80 surface of the end of the arm 352 to a nut 357 secured to the end of the rod 354. Below the end of the arm 352 there is secured to the rod 354 a collar 358. It will be understood that upward movement of the rod 354 moves the wedge 344 outwardly into inoperative position, whereas downward movement of the rod 354 will cause movement of the wedge 344 into operative position, the pressure being a 85 yielding pressure through the spring 356 so that in case the wedge 344 comes down upon the exposed portion of the pin 346 no damage 90 will be done, the cam wheel 70 and pin 346 continuing to rotate with the part 350 until the extreme edge of the cam or wedge 344 can engage with the shoulder on the pin 346 to 95 retract the pin. In order to move the rod 354 in up and down directions there is provided a collar 360 (Fig. 2) secured to the rod 100 adjacent to its lower end, the said collar carrying a cam projection 362 with which there 105 cooperates an inclined slotted cam member 364 at the end of a lever 366 fixed to a pivot pin 368 mounted in bearings 370 extending laterally from the standard 372 of the machine frame, the outer end of the lever 366 carrying a forked member 374 with which the knee of the operator may be engaged to rock the lever 366 and thus through the cooperation 110 of the cam member 364 and the cam projection 362 raise or lower the rod 354. Clamped on the rod 354 is an arm 376 having 115 its other end slidably engaged with the upper end of the pivot pin 368, the purpose of the arm 376 being to prevent rotation of the said rod, thereby holding the cam projection 362 in the slot of the cam member 364. Conveniently a pin 377 is provided backed by a spring 379 and operative to engage in shallow 120 125 de- 130

pressions in the lever 366 to retain the lever and hence the wedge 344 in adjusted position.

In the preferred embodiment of the invention shown, the cam 70 is shaped to relax the tension of the spring 72, if it be under tension due to a strong updraw on the upper of the shoe, and then to depress bodily the gripper jaws 30, 42 the cam being timed to act in predetermined relation to the movement of the nose 212 to overlay the upper on the sole, as indicated in Figs. 13 and 14, the gripper moving downwardly as the overlaying member 212 moves to press the upper down upon the sole. Preferably and as shown the last part of the movement of the nose 212 effects a pressing of the upper into firm contact with the sole and with the upstanding lip or rib at the angle of junction of the latter with the sole.

In operating with this machine to side-last a welt shoe the gripper jaws 30, 42, after closing on an edge portion of the upper, move upwardly as the sleeve 36 slides through the bearing 38. At this time the work rest 150 is engaged with the surface of the insole, the end of the work rest being so shaped as to afford a backing for the lip or rib of the insole and to engage snugly in the angle or channel between the lip or rib and the body of the insole. It is intended that the operator shall hold the shoe at an inclination to the horizontal somewhat less than the inclination of the driver 204 and the member 212 (Fig. 12). Hence, on the updraw movement of the gripper the upper will be tensioned over the last in such a manner as to stand out somewhat from the last, as indicated in Fig. 12, one purpose being to avoid engagement of the upwardly moving upper with the edge of the insole at this step of the proceedings so as to obviate the possibility of displacing the edge of the insole or even of turning it over, as might happen if the insole material were relatively thin. In the next step the gripper moves horizontally toward the front of the machine in what is commonly termed the overdraw movement, this step being illustrated in Fig. 13 of the drawings, it being obvious that the work rest 150 prevents not only the upward movement of the work but also movement away from the fastening inserting means, as represented by the nose portion 212 thereof. It will be clear then that the end of the work rest at this step is firmly engaged with both the upper face of the insole and the back of the lip or rib. As the gripper moves over the insole in the overdraw movement, the inserting mechanism advances and as the nose portion 212 starts its overlaying action on the upper the gripper is moved downwardly toward the insole without releasing the upper, Figs. 13 and 14 illustrating the operation by which the upper is fully laid in over the edge of the insole and into

the angle between the margin of the insole and the upstanding lip or rib.

In the machine herein shown, it is only after the fastening has been fully driven and clinched against the end of the work rest, 70 which serves also as an anvil, that the gripper releases the edge of the upper, as shown in Fig. 15. It will be evident by reference to Figs. 13 and 14 that the overlaying member 212 engages the tensioned margin of the upper in a location between the gripper and the edge of the insole and spaced a substantial distance from said edge, and that its movement is in a direction inclined to the plane of the insole, the construction and arrangement being such that throughout the action of this member on the upper its pressure is substantially localized at a distance from the edge of the insole. The effect accordingly is that the member 212 wraps the upper about the edge, 85 of the insole and lays or tucks it into the angle between the feather and the lip without danger of displacing the edge portion of the insole by pressure against it or of otherwise damaging the shoe, while at the same time 90 drawing the upper tightly over the last and insole unopposed by excessive friction between the upper and the edge of the insole and with the assistance of the gripper which continues to hold the upper under tension but with a pulling force automatically adjusted to the action of the overlaying member so as to avoid excessive strain on the upper. That is to say, the gripper, by its downward movement toward the insole, counteracts to a substantial degree the tendency of the overlaying member to increase the strain or tension on the upper, and thus prevents excessive tension while facilitating the laying of the upper into close contact with the insole. It will also 100 be evident that the staples are driven in the same direction as that of the overlaying movement of the member 212, and that they are thus inclined inwardly toward the base of the lip of the insole (Fig. 15) which assists 105 materially in holding the upper tight without too great a strain on the lip.

In operating upon a McKay shoe it is preferable to substitute for the work rest 150 a work rest 150^a (Figs. 16, 17, 18) which differs 110 from work rest 150 in having clinching surfaces located even nearer to the lower edge of the end surface thereof, so that the fastening in the McKay work will be clinched as close down into the groove or channel as it is practicable to get it. This arrangement has the further advantage of facilitating the operation of smoothing down the lip, to which the upper has been fastened, as a preliminary to the application of the outsole. It will be noted that with the lip of the McKay insole inclined as illustrated relatively to the plane of the insole, which is an advantage in that it facilitates the subsequent laying down of the lip, it lies substantially perpendicular to the di- 115 120 125 130

rection in which the staples are driven, so that the staples are substantially or approximately perpendicular to the lip. When the lip is turned down the effect accordingly is to tip the staples more or less toward a perpendicular relation to the plane of the insole, with a resulting tendency further to tighten the upper.

Among the decided advantages of the co-operation between the work rest 150, the gripper and the member 212 in the lasting operations are those relating to the uniformity of the insertion of the fastenings relatively to the plane of the insole, so that in welt work, for example, they will bear a definite predetermined relation to the inseam sewing and trimming operations, and the very effective overlaying of the upper by the member 212 in cooperation with the gripper, so that a more than ordinarily good surface is provided upon which to lay the welt, thus making the work easier for the operator in succeeding operations and resulting in a better shoe.

In the operations of side-lasting McKay 25 shoes it will be noted that the gripper should travel a greater distance between the edge of the shoe and the work rest than in lasting, welt shoes since the distance between the up-standing lip and the marginal edge of the 30 insole is greater in McKay shoes than in welt shoes, as will be clear from a comparison of Figs. 13 and 16. Hence, for operating on McKay shoes the cam 114 on the cam wheel 88 may be replaced by a similarly shaped cam 35 which will cause the roll 112 and, therefore, the slide 40, to move further to the right in Fig. 2, thereby giving a greater movement to the gripper into position to grip the upper. In lasting the McKay shoe the gripper moves 40 step by step just as in the side lasting operations on the welt shoe, that is, first the up-draw movement, somewhat away from the edge of the insole, as indicated in dotted lines in Fig. 16, followed by the overdraw movement in which the upper finally reaches the 45 position shown in Fig. 16, just at the time that the nose 212 reaches the upper. Subsequently the gripper is moved downwardly as the member 212 moves inwardly in its operation just 50 as in the similar movement, illustrated in Fig. 14, on the welt shoe. Finally the fastening is inserted and clinched before the gripper lets go, as indicated in Figs. 17 and 18 combined. It will be understood that the 55 distance between the end of the member 212 in its retracted position and the end of the work rest is the same for both work rests 150 and 150a.

If desired different portions of the shoe 60 may be operated upon in the following manner. Referring to Figs. 19 and 20, the first staple will be inserted at *a*, the second at *b*, the third at *c*, that is, spaced at rather considerable distances with respect to each other. 65 These fastenings at *a*, *b* and *c* are inserted,

using the updraw movement of the gripper, with its other movements, and because the fastenings are spaced so far apart it is possible to utilize the spring at 72 tensioned to the highest point by adjustment of the block 130 on the updraw lever 54, thereby exerting enough tension to make it almost equivalent to a pulling-over operation. It will be understood that if this were attempted with the fastenings placed closely adjacent to each other, one or more of the fastenings might be pulled out by the force of the pull applied to the upper. Subsequently the updraw movement of the gripper is discontinued, in the manner already disclosed, and intermediate fastenings *d*, *e* and *f* inserted using only the overdraw movement of the gripper. Incidentally, Fig. 19 shows the results of side lasting operations on a welt shoe and Fig. 20 of similar lasting operations on a McKay shoe.

In certain classes of work, and especially where the upper has not been skimped, it may be desirable to dispense with the updraw movement of the gripper in side-lasting along the shank portion of the shoe as distinguished from the forepart and those portions of the upper just at the rear of the ball line of the insole, since it is possible to get the requisite tension on this part of the upper, and particularly on the inside of the shank, by utilizing only the overdraw movement of the gripper and the overlaying action of the nose 212. This will be made clear from an inspection of Fig. 21 and particularly in comparison of this figure and Fig. 12. In lasting along the forepart of the shoe the upper should be carried outwardly in the updraw of the gripper in order to avoid contact with the edge of the insole, as will be obvious from an inspection of Figs. 12 and 13, the overdraw taking place as a subsequent operation. It will be clear, however, from the showing in Fig. 21 that there is no danger of the overdraw movement displacing the edge of the insole at the shank portion *s* of the last *L* since the upper will be lying over at a considerable angle before it contacts with the edge of the insole at this portion where it is narrow, and hence the updraw of the gripper may be dispensed with and the upper carried in and laid upon the insole by an overdraw movement of the gripper jaws 42, 30, without a prior updraw movement, the nose 212 following in with the gripper and pressing the upper into contact with the lip or rib of the insole. This is especially advantageous in lasting the shank portion of the upper on the inner side of the shoe where the upper extends up far enough to be seized by the gripper and to be laid over against the insole by an overdraw movement only of the gripper. An updraw on this part of the upper might on some kinds of work displace and distort the lines of the shoe, more particularly

in low shoes, since there is not the same resistance to an updraw movement as in the forepart of the upper which extends over the last from one side to the other. As heretofore stated, adjacent portions of the upper, that is, along the forepart of the shoe, are subjected to updraw movements as well as overdraw movements of the gripper, and since the lasting of the forepart will take place before the lasting of the shank portion on the inner side of the shoe, the upper is so well positioned by these prior lasting operations that no difficulty is experienced in manipulating the shoe to cause the gripper to seize the upper in the shank portion to overdraw the same as a preliminary to the insertion of the fastening.

In the manufacture of some shoes, especially those of a style and size such as to present a pronounced inward curvature at the edge of the last bottom on one or both sides at the rear of the ball line, it may be preferable to pull preliminarily and fasten portions of the upper in the locations where the edge 25 of the sole curves inwardly toward the shank, since in these locations the upper may be safely subjected to a hard pull, and such a pull may be required for the best results. In order to avoid distortion of the upper, and 30 for better uniformity in the results, it is contemplated that under some conditions it will be advantageous that such a pull be applied simultaneously at the opposite sides of the shoe, for example by the use of a machine 35 such as illustrated in the prior application of Bernhardt Jorgensen hereinbefore referred to. A shoe which has been subjected to this treatment is illustrated in Fig. 22. The stretch is thus taken out of the upper in the 40 locations where the hardest pull is required, and the portions of the upper in the shank also are drawn inwardly to a better position for the operation of the side lasting machine. This manner of treatment will facilitate the 45 proper insertion of the lasting staples and will insure that the lip of the sole, after the lasting, will not be subjected to an excessive degree of outward pull by the reaction of the upper. In Fig. 22, the side grippers 390 50 of the Jorgensen machine are shown in dotted lines in the position they occupy at the end of the stretching of the upper. The holding tacks 392 are inserted and the shoe subsequently presented to the side lasting machine 55 herein described.

In addition to advantages such as hereinbefore set forth, it should be noted that the use of a machine constructed and operating as herein disclosed requires less care and attention in manipulating the work in order to secure good results, and involves less fatigue of the operator, than is the case with machines such as commonly used heretofore for progressively lasting shoes. Since the overlaying member is arranged to move in a di-

rection inclined to the plane of the sole with a bending and pressing effect on the upper, rather than a wiping effect, it is not necessary that the shoe be held in such an exact angular relation to this member as where a wiper movable in a direction parallel to the plane of the sole is utilized to effect the overlaying operation; there being no danger that small variations in the positioning of the shoe relatively to the overlaying member may result either in damage to the shoe or in too light pressure to hold the upper effectively against loss of tension, such as there is in the use of machines having a wiper operating close to the edge of the sole and against which the shoe should be pressed up firmly by the operator until the upper is fastened. The necessity for pressing the shoe up hard against the overlaying member in the machine herein shown is further obviated by reason of the fact that the gripper continues its pull on the upper until the overlaying member has arrived at the end of its operative movement; and for this among other reasons also the production of a tightly lasted shoe does not require that the machine be operated with as great updrawing and overdrawing tension as it has been customary to utilize heretofore, so that there is less tendency for the pull of the gripper to displace the shoe in the hands of the operator. Moreover, in operating upon shoes having lipped insoles the channel guide or work rest, by engagement with the lip of the insole, determines the path of the shoe, thus making it easy to guide the work, and also acts as an abutment against the overdraw pull of the gripper, the pressure of the overlaying member and the force of the staple driver, thereby further relieving the operator of the necessity of using a high degree of force in supporting the shoe.

Important novel aspects of the method herein disclosed of making McKay shoes are claimed in a continuing application, Serial No. 721,007, filed on June 19, 1924.

Having thus described my invention, what I claim as new and desire to secure by Letters Patent of the United States is:—

1. In a machine of the character described, a stationary work rest having an anvil on its operative end, means for tensioning the work against the resistance of the work rest, and fastening means arranged relatively to the work rest to insert fastenings through the work and clinch them against the anvil, said fastening means comprising an inside former located out of the line of fastening insertion, an outside former movable to form a fastening over the inside former and to carry the fastening into the line of fastening insertion, and a driver movable to drive the fastening into the work.

2. In a machine of the character described, a combined anvil and work rest, gripper mechanism for tensioning the work against

the resistance of the work rest, and fastening forming and inserting means comprising a stationary inside former located above the plane of fastening insertion, an outside former movable to form a staple fastening over the inside former and to transport the formed staple to the line of fastening insertion, and a staple driver movable to insert fastenings through the work and clinch the same against the anvil.

3. A lasting machine having a work rest, gripper means for pulling the upper of a shoe over a last, an inside former for a staple fastening located out of the line of fastening insertion, an outside former movable to form the staple over the inside former and to transport the staple to the line of fastening insertion, and a driver for driving the staple fastening to secure the upper to the sole after the gripper means has pulled the upper.

4. In a machine of the character described, a work rest, gripper mechanism for pulling the upper of a shoe over a last positioned by the work rest, fastening inserting means for driving fastenings in directions inclined toward the bottom face of the last to secure the upper to the lip or shoulder of a sole on the last, and power means for operating the gripper mechanism and the fastening inserting means so as to insert each fastening before the upper is released by the gripper mechanism.

5. In a machine of the character described, a work rest, a gripper for seizing the edge portion of an upper and pulling it over a last positioned by the work rest, fastening inserting means movable toward the work rest in a direction inclined toward the bottom face of the last and having a nose portion operative to work the upper over a sole on the last, and means for operating the gripper and the fastening inserting means in timed relation so that the upper is worked into final position and the fastening inserted prior to the release of the upper by the gripper.

6. In a machine of the character described, a work rest, a gripper for pulling the upper of a shoe over a last, fastening inserting means for inserting fastenings to secure the upper to a sole on the last, means for imparting to the gripper an updraw movement and then an overdraw movement prior to the insertion of a fastening, and means under the control of the operator for discontinuing the updraw movement of the gripper while maintaining it still effective to overdraw the upper so that fastenings may be inserted at intervals following overdraw movements only of the gripper.

7. In a machine of the character described, a work rest, a gripper for pulling the upper of a shoe over a last positioned by the work rest, fastening inserting means having a nose portion for working the upper into firm con-

tact with the marginal portion of a sole on the last, a driver for inserting a fastening into the upper and the sole in a direction inclined toward the bottom face of the last, and means for operating the gripper and the driver to insert the fastening and then to cause the gripper to release the upper.

8. In a machine of the character described, a work rest, a gripper for pulling the upper of a shoe over a last, means for inserting fastenings to secure the upper to a sole on the last, means for operating the gripper to effect an updraw movement thereof and subsequently an overdraw movement prior to the insertion of the fastening, and a knee lever having connections for controlling the gripper operating means to discontinue the updraw movement of the gripper so that the latter may have an overdraw movement only in engagement with the upper prior to the insertion of the fastening.

9. In a machine of the class described, a work rest for positioning a shoe to be lasted, gripper means for seizing successively edge portions of the upper on the last, an overlaying member, and means for moving the gripper means first upwardly in a direction to tension the upper on the last, then inwardly to carry the upper over the edge of the insole on the last and then downwardly to adjust the force of the pull on the upper to the action of the overlaying member and finally to release the upper after the insertion of a fastening.

10. In a machine of the character described, a combined work rest and anvil adapted to engage the lip or shoulder of a sole on a last, fastening inserting means having a portion adapted to work an upper over the sole and to co-operate with the anvil in inserting a fastening, gripper means for seizing the upper successively at points along its edge portion, and means for operating the gripper means to cause an updraw movement thereof in a direction to draw the upper outwardly away from the edge of the sole on the last and then an overdraw movement to carry the upper over the edge of the sole on the last and to maintain tension on the upper until a fastening has been driven through the upper and into the lip or shoulder of the sole.

11. In a machine of the character described, a combined work rest and anvil for engagement with the lip or shoulder of a sole on a last, gripper means for seizing the upper successively at points along the edge portion thereof, means for causing the gripper means to tension the upper and to carry it over the edge of the sole, and a fastening inserting means having a nose portion inclined at an angle to the horizontal and arranged to engage the upper while it is held by the gripper means and through movement of the nose portion at an angle to the bottom surface of the sole to work the upper over the edge

of the sole and to clamp an edge portion thereof firmly against the lip or shoulder backed by the work rest and to co-operate in the insertion of a fastening prior to the release of the upper by the gripper means.

12. In a machine of the character described, a combined anvil and work rest for engaging the lip or shoulder of a sole on a last, gripper means for engaging an upper successively at points along the edge portion thereof, means for causing the gripper means to tension the upper about the last and to draw it over the edge portion of the sole, and a fastening inserting means comprising a slide movable in a direction inclined toward the bottom face of the last and having a portion adapted to engage the edge portion of the upper while the latter is held by the gripper means to work the upper into the angle at the base of the lip or shoulder on the sole and to clamp the upper against said lip or shoulder while a fastening is being driven and the upper is still held by the gripper means.

13. In a machine of the character described, a combined work rest and anvil for engaging the lip or shoulder of a sole on a last, fastening inserting means having a portion for working an upper over the edge of the sole and for clamping the upper and lip or shoulder in co-operation with the combined work rest and anvil, a gripper normally operative to updraw the upper to tension the same on the last and then to overdraw the edge portion of the upper with respect to the edge portion of the sole and to hold the upper until a fastening has been inserted, and means under the control of the operator for discontinuing the updraw movement of the gripper while the gripper continues operative to overdraw the upper.

14. In a machine of the character described, a work rest adapted to engage the lip or shoulder of a sole on a last, fastening inserting means for securing an upper to the lip or shoulder by a row of fastenings, gripper means for seizing the upper successively at points along its edge portion, and means for operating the gripper means to cause an updraw movement thereof in a direction to draw the upper outwardly away from the edge of the sole and then an overdraw movement to carry the upper over the edge of the sole and to maintain tension on the upper until a fastening has been inserted through the upper and into the lip or shoulder of the sole.

15. In a machine of the character described, a work rest for engaging the lip or shoulder of a sole on a last, fastening inserting means for securing an upper to the lip or shoulder by a row of fastenings, a gripper normally operative to updraw the upper to tension the same on the last and then to overdraw the edge portion of the upper with respect to the

edge portion of the sole and to hold the upper until it has been secured in lasted condition, and means under the control of the operator for discontinuing the updraw movement of the gripper while continuing its overdraw movement in engagement with the upper to co-operate with the work rest and the fastening inserting means in lasting operations on the shoe at points selected by the operator.

16. In a machine of the character described, a work rest serving as an abutment for positioning work, gripper mechanism for seizing a portion of the work to tension the same prior to the insertion of a fastening, and fastening forming and inserting devices comprising a nose portion movable toward the work rest while the gripper mechanism maintains the tension on the work, said forming devices being operative in a plane above the plane of fastening insertion to form the fastening and then to transfer it to the inserting devices.

17. In a machine of the character described, a work rest serving as an abutment for locating a piece of work, a gripper for tensioning a portion of the work, means for causing an updraw movement of the gripper, means for causing an overdraw movement of the gripper, and means for discontinuing the updraw movement of the gripper without affecting its overdrawing action on the work.

18. In a machine of the character described, a work rest serving as an abutment for positioning a piece of work, a gripper for tensioning a portion of the work, means for causing an updraw movement of the gripper, means for causing an overdraw movement of the gripper, a shaft common to both of said means, a cam on the shaft for operating the updraw means, a clutch for connecting the cam to the shaft, and connections under the control of the operator for unclutching the cam so as to discontinue the updraw movement with the gripper in position to effect overdrawing only of the work.

19. In a machine of the class described, a gripper for pulling an upper over a last and inwardly over the bottom of a sole on the last, means for laying the marginal portion of the upper over the bottom of the sole, and gripper-controlling mechanism constructed to move the gripper toward the bottom of the sole while holding the upper under tension in the operation of the overlaying means on the upper to prevent an excess of tension on the upper from the action of the overlaying means.

20. In a machine of the character described, a work rest serving as an abutment for positioning a piece of work, fastening inserting means, a gripper for tensioning portions of the work prior to insertion of fastenings, means for causing an updraw movement of the gripper followed by an

overdraw movement thereof prior to the insertion of each fastening, and means for discontinuing the updraw movement of the gripper after the insertion of one or more fastenings while continuing the overdrawing action of the gripper preparatory to the insertion of other fastenings.

21. In a machine of the character described, a work rest serving as an abutment to position a piece of work, fastening inserting means, a gripper for tensioning portions of the work prior to the insertion of fastenings, means for causing updraw and overdraw movements of the gripper to tension portions of the work and to hold them each under tension until a fastening is inserted, and means for discontinuing the updraw movements of the gripper after the insertion of one or more fastenings while maintaining the gripper effective to overdraw the work and to hold it under tension until other fastenings are inserted.

22. In a machine of the character described, a work rest serving as an abutment for positioning a piece of work, fastening inserting means, a gripper for tensioning a portion of the work prior to insertion of a fastening, and gripper controlling means for causing an updraw movement of the gripper and subsequently as a separate movement an overdraw movement of the gripper constructed to hold the work under tension until the fastening is inserted.

23. In a machine of the character described, a work rest serving as an abutment for positioning a piece of work, fastening inserting mechanism, a gripper for tensioning a portion of the work prior to the insertion of a fastening, means for causing an updraw movement of the gripper, and means operating subsequently to the first-mentioned means for causing an overdraw movement of the gripper, the construction and arrangement being such that the gripper maintains the work under tension until the fastening is inserted.

24. In a machine of the character described, a work rest serving as an abutment to position a piece of work, fastening inserting means comprising a fastening guiding nose, a gripper for tensioning a portion of the work, gripper-operating means for causing an updraw movement of the gripper followed by an overdraw movement and then a downward movement without releasing the work, and means for operating the fastening inserting means to project the nose into contact with the work while under tension by the gripper so that the nose and the gripper cooperate in tensioning the work and in maintaining it under tension until a fastening is inserted.

25. In a machine of the character described, a work rest serving as an abutment for positioning a piece of work and for clenching a fastening driven into the work,

fastening inserting means, a gripper for tensioning a portion of the work prior to insertion of the fastening, and means for causing an updraw movement of the gripper in a direction inclined outwardly away from the edge of a piece of work positioned by the abutment and, subsequently as a separate movement, an overdraw movement of the gripper prior to the insertion of a fastening.

26. In a machine of the character described, a work rest serving as an abutment for positioning the work, gripper mechanism for seizing a portion of the work to tension the same prior to the insertion of a fastening, and fastening forming and inserting devices for inserting a fastening while the gripper mechanism maintains the tension on the work, said forming devices being operative in a plane above the plane of fastening insertion to form the fastening and then to transfer it to the inserting devices.

27. In a machine of the character described, a work rest serving as an abutment for positioning a piece of work and for clenching a fastening driven into the work, fastening inserting means, a gripper for tensioning a portion of the work prior to the insertion of a fastening, means for causing an updraw movement of the gripper in a direction inclined outwardly away from the edge of a piece of work positioned by the abutment, and means operating subsequently to the first-named means for causing an overdraw movement of the gripper.

28. In a machine of the character described, a work rest serving as an abutment for positioning a piece of work, a gripper for tensioning a portion of the work, operating means for causing an updraw movement of the gripper, means for discontinuing the updraw movement of the gripper arranged to leave the gripper at a predetermined point in its updraw movement, and means for causing an overdraw movement of the gripper in gripping engagement with the upper while it is maintained at the level established by the discontinuing means.

29. In a machine of the character described, a work rest for engagement with the sole of a shoe on a last, a gripper for seizing the upper successively at points along the forepart edge portion thereof to work the forepart portions of the upper over the last and into lasted relation with respect to the sole, means for causing updraw movements of the gripper, means under the control of the operator for disconnecting the updraw operating means from its source of power arranged to position the gripper at a predetermined point in its updraw movement, and means for causing an overdraw movement of the gripper to last shank portions of the upper without a prior updraw on these portions of the upper.

30. In a machine of the character de-

scribed, a combined work rest and anvil for engagement with the lip or shoulder of a sole on a last, a gripper for seizing the upper successively at points along the edge portion thereof, operating means for moving the gripper to updraw the upper, means under the control of the operator for disconnecting the updraw operating means at a predetermined point in the updraw movement of the gripper and maintaining it there, means for causing overdraw movements of the gripper in engagement with the upper while the updraw means is inoperative, and fastening inserting means for inserting fastenings successively through the upper and through the lip or shoulder of the sole while the gripper maintains the upper under tension at the end of its overdraw movements only.

31. A machine for progressively lasting shoes having, in combination, means for gripping and pulling the upper in different locations successively along the sides of a shoe, means for laying each of the tensioned portions of the upper over the bottom of the sole by pressure substantially localized throughout the overlaying operation at a distance from the edge of the sole and directed at an angle to the plane of the sole toward its bottom face while the upper is held under tension, and means for fastening the upper in lasted position.

32. A machine for lasting shoes having, in combination, a gripper and means for operating it to pull the upper, an overlaying member movable in a direction inclined to the plane of the sole toward its bottom face to lay a portion of the upper over the bottom of the sole, and automatic means to cause the gripper to approach the plane of the sole while retaining its hold on the upper in the overlaying operation.

33. A machine for lasting shoes having, in combination, means for pulling the upper, a member movable in a direction inclined to the plane of the sole toward its bottom face to lay the upper over the bottom face of the sole without any substantial wiping effect thereon, and means for driving a fastening in a direction inclined to the plane of the sole to fasten the upper to the sole.

34. A machine for lasting shoes having, in combination, a gripper and means for operating it to pull the upper, a member movable in a direction inclined to the plane of the sole toward its bottom face to lay the upper over the bottom face of the sole, means for fastening the upper, and means to cause the gripper to retain its hold on the upper until after the fastening is inserted.

35. That improvement in methods of making shoes which comprises tensioning an upper over the side of a last by a pull in a direction inclined outwardly away from the edge of a sole on the last, then carrying the edge portion of the upper inwardly over the

edge of the sole on the last, and subsequently securing the upper to the sole while maintaining the pull on the upper.

36. That improvement in methods of making shoes which comprises tensioning an upper over the side of the last by a pull in a direction inclined outwardly away from the edge of a sole on the last, then carrying the edge portion of the upper inwardly over the edge portion of the sole on the last, working this edge portion of the upper into contact with the margin of the sole and with an upstanding lip or shoulder of the sole, and inserting a fastening while the upper is still held under tension.

37. That improvement in methods of making shoes which comprises tensioning an upper over the side of the last by an updraw movement, then carrying the edge portion of the upper inwardly over the edge portion of a sole on the last while maintaining the tension, while the upper is held in lasted condition inserting a fastening to secure the upper to the sole, repeating these operations at spaced intervals along each side of the shoe, and subsequently completing the lasting of the upper in the spaces between the already inserted fastenings by an overdraw movement unaccompanied by a prior updraw on the upper and followed by the insertion of a fastening in each location to secure the upper in lasted position.

38. That improvement in methods of making shoes which comprises tensioning an upper over the side of the last by an updraw movement, then while maintaining the upper under tension carrying it inwardly by an overdraw movement into contact with the edge portion of a sole on the last and working the upper into contact with the sole and with an upstanding lip or shoulder thereof, simultaneously with the termination of the overworking operation inserting a fastening, repeating these operations at points considerably spaced from each other along each side of the shoe, and completing the side lasting of the shoe by pulling the upper inwardly over the last by an overdraw movement without the preliminary updraw movement before mentioned and working the upper into contact with the sole and inserting a fastening at the termination of each overworking operation to secure the upper to the sole.

39. That improvement in methods of making shoes which comprises tensioning an upper over the side of a last by an updraw movement, then carrying the edge portion of the upper by an overdraw movement into position over the edge portion of a sole on the last, working the upper into contact with the marginal portion of the sole and forcing it into the angle made by an upstanding lip or shoulder of the sole and the body portion thereof and finally inserting a fastening to secure the upper to the lip or shoulder while

it is still under tension, repeating this operation along the forepart and along those portions of the upper just to the rear of the ball line of the sole on each side of the shoe, and completing the side-lasting of the shoe in the shank portion thereof by tensioning the upper by overdraw movements as distinguished from the updraw and overdraw movements along other parts of the shoe and 10 securing the overdrawn parts of the upper to the sole by spaced fastenings.

40. That improvement in methods of making shoes which comprises tensioning an upper over the side of a last by an updraw movement, then carrying the edge portion of the upper by an overdraw movement into position over the edge portion of a sole on the last, and finally inserting a fastening to secure the upper in lasted condition while 20 it is still under tension, repeating this operation along the forepart and along those portions of the upper just to the rear of the ball line of the sole on each side of the shoe, and completing the side lasting of the shoe in the shank portion thereof by tensioning the upper by overdraw movements as distinguished from the updraw and overdraw movements along other parts of the shoe and 25 securing the overdrawn parts of the upper to the sole by spaced fastenings.

41. That improvement in methods of lasting shoes which consists in working those portions of the upper where the upper extends continuously across the last over the 35 last by updraw and overdraw movements and securing each updrawn and overdrawn portion to the insole, tensioning other portions of the upper by overdraw movements only, and securing the overdrawn portions 40 to the insole in lasted position.

42. That improvement in methods of making shoes which consists in gripping and pulling an upper to tension it relatively to a last and to a sole on the last, and while 45 holding the upper under tension forcing it into the angle between the margin and the lip or shoulder of the sole by pressure applied initially at a substantial distance from the plane of the sole and in a direction at a substantial angle to the plane of the sole and confined substantially to a location at a distance from the edge of the sole.

43. That improvement in methods of making shoes which consists in tensioning an upper over a last and pulling it inwardly over the margin of a sole on the last, and while holding the upper under tension laying a portion of it over the margin of the sole by pressure applied initially and throughout 55 the overlaying operation at a distance from the edge of the sole and in a direction at a substantial inclination to the plane of the sole toward the bottom face of the sole.

44. That improvement in methods of making shoes which consists in gripping the

margin of an upper and pulling it to tension the upper relatively to a last and to a sole on the last, engaging the tensioned marginal portion of the upper in a location spaced from the edge of the sole, and by pressure substantially confined to this location and applied in a direction inclined toward the plane of the sole tucking the upper into the angle between the margin and the lip or shoulder of the sole.

45. That improvement in methods of making shoes which consists in gripping the margin of an upper and pulling it to tension the upper relatively to a last and to a sole on the last, tucking the tensioned marginal portion of the upper into the angle between the margin and the lip or shoulder of the sole by pressure applied in a direction inclined at a substantial angle to the plane of the sole, fastening the upper, and thereafter releasing the grip on the upper.

46. That improvement in methods of lasting shoes which consists in gripping a portion of the margin of an upper and pulling it to tension the upper relatively to a last and to a sole on the last, laying the tensioned marginal portion of the upper inwardly over the sole by pressure applied initially at a distance from the edge of the sole and in a direction inclined at a substantial angle to the plane of the sole toward the bottom face of the sole while holding the upper under tension, fastening the overlaid portion of the upper to the sole while holding it with pressure thus localized at a distance from the edge of the sole, and repeating said pulling, overlaying and fastening operations on different portions of the upper successively along the edge of the shoe bottom.

47. That improvement in methods of making shoes which consists in pulling an upper over a last and inwardly over the margin of a sole on the last at an inclination to the plane of the sole, and laying the tensioned marginal portion of the upper over the margin of the sole by pressure applied initially at a distance from the edge of the sole and in a direction substantially normal to the direction of the inward pull on the margin.

48. That improvement in methods of making shoes which consists in pulling an upper over a last and tensioning a portion of it across the edge face of a sole, laying a portion of the upper while under tension over the margin of the sole in parallel relation to the plane of the sole by pressure applied initially at a distance above the edge of the sole and in a direction inclined to the plane of the sole, and while holding the upper in overlaid position by pressure substantially localized at a distance from the edge of the sole fastening it in overlaid position by a fastening driven at a substantial angle to the plane of the sole.

49. That improvement in methods of making shoes which consists in gripping the mar-

gin of an upper and tensioning it relatively to a last and to a sole on the last by pulling it in a direction inclined outwardly from the edge of the sole, thereafter pulling the marginal portion of the upper inwardly over the sole, laying a portion of the upper while under tension in substantially parallel relation to the plane of the sole by engaging it at a substantial distance from the edge of the sole 10 and from the location where it is gripped and pressing it down in a direction inclined to the plane of the sole, and thereafter fastening the upper to the sole.

50. That improvement in methods of making shoes which consists in gripping the margin of an upper and tensioning it relatively to a last and to a sole on the last by pulling it in a direction inclined outwardly from the edge of the sole, thereafter pulling the marginal portion of the upper inwardly over the margin of the sole, engaging the inwardly pulled portion of the upper in a location spaced a substantial distance from the edge of the sole and by applying pressure in said location in a direction inclined at a substantial angle to the plane of the sole tucking the upper into the angle between the margin and the lip or shoulder of the sole while holding the upper in tensioned condition.

51. That improvement in methods of making shoes which consists in gripping and pulling an upper to tension it relatively to a last and to a sole on the last, forcing a portion of the upper while under tension into the angle between the margin and the lip or shoulder of the sole by pressure applied in a direction at a substantial inclination to the plane of the sole and toward the bottom face of the sole, and while holding the upper in said angle 40 fastening it permanently to the shoulder or lip of the sole.

52. That improvement in methods of making shoes which consists in gripping and pulling an upper to tension it relatively to a last and to a sole on the last, laying the upper inwardly over the margin of the sole, and while continuing the overlaying pressure inserting a staple through the upper and into the lip or shoulder of the sole in a direction 50 inclined to the plane of the sole.

53. That improvement in methods of making shoes which consists in gripping and pulling an upper to tension it relatively to a last and to a sole on the last, laying the upper inwardly over the margin of the sole by pressure applied in a direction inclined to the plane of the sole while the upper is held under tension, and inserting a fastening substantially the same direction in which said pressure is applied to fasten the upper to the lip or shoulder of the sole.

54. That improvement in methods of lasting shoes which consists in pulling successively different portions of an upper to tension the upper relatively to a last and to a sole on

the last, laying the upper inwardly over the margin of the sole at each portion of the shoe where the pull is applied by pressure applied at an inclination to the plane of the sole, and fastening each overlayed portion of the upper to the lip or shoulder of the sole by driving a fastening into said lip or shoulder in a direction inclined inwardly toward the bottom of the last.

55. That improvement in methods of making shoes which consists in pulling an upper over a last and over the margin of a sole provided with a channel lip, forcing the upper into the angle between the margin of the sole and said lip by pressure applied in a direction inclined to the plane of the sole toward the bottom face of the sole, and fastening the upper to said channel lip by driving a staple through the upper and the lip in a direction inclined to the plane of the sole toward the base of said lip.

56. That improvement in methods of making shoes which consists in gripping and pulling an upper successively in different locations to tension it relatively to a last and to a sole on the last, working the upper inwardly over the margin of the sole in each of said locations, and while thus working the upper inwardly holding it under tension with an unslipping grip and without substantial increase of the tension.

57. That improvement in methods of making shoes which consists in gripping and pulling an upper to tension it relatively to a last and to a sole on the last, then engaging the tensioned marginal portion of the upper in a location spaced substantially from the edge of the sole and laying it inwardly over the margin of the sole by pressure applied in said location in a direction at a substantial inclination to the plane of the sole, and while thus laying the upper inwardly holding it under tension while adjusting the tension in accordance with the overlaying pressure to prevent excessive strain on the upper.

58. That improvement in methods of lasting shoes which consists in gripping and pulling different portions of an upper successively, forcing the upper into the angle between the margin and the lip or shoulder of a sole at each portion of the shoe where the pull is applied and fastening it to the sole, and while thus forcing each portion of the upper inwardly holding the upper in that location under a pulling tension so proportioned as to prevent substantial increase in the strain on the upper in forcing it into said angle.

59. That improvement in methods of lasting shoes which consists in pulling an upper and fastening it to a sole in spaced locations along a side of the shoe, and thereafter subjecting the upper in the intervals between said locations to different pulling treatment from the portions first operated on to work

70

130

it into lasted relation to the sole and fastening it in said intervals.

60. That improvement in methods of lasting shoes which consists in pulling an upper heightwise of a last and working it inwardly and fastening it in a plurality of locations along a side of the shoe spaced apart sufficiently to prevent loosening a previously inserted fastening by the pull applied to the upper, and thereafter lasting the upper in the intervals between said locations by pulling it only in directions transverse to the height of the last.

61. That improvement in methods of lasting shoes which consists in subjecting different portions of an upper successively along the side of a shoe to an updrawing and an overdrawing pull and inserting fastenings to hold the upper in the different locations where the pulls are applied, and thereafter lasting the upper in the intervals between said locations by subjecting it to an overdrawing pull only and fastening it.

62. That improvement in methods of lasting shoes which consists in operating successively on different portions of an upper along the side of a shoe to pull the upper heightwise of the last and work it inwardly and fasten it to the lip or shoulder of the sole in locations sufficiently spaced to prevent loosening a previously inserted fastening by the pull applied to the upper, and thereafter operating upon the upper in the intervals between said locations with inwardly directed force only to work it into lasted position and inserting fastenings to secure it to the lip or shoulder of the sole.

63. That improvement in methods of lasting shoes which consists in subjecting different portions of an upper along the side of a shoe to an updrawing and an overdrawing pull and inserting staples to fasten the upper to the lip or shoulder of the sole at intervals sufficiently spaced to prevent loosening a previously inserted staple by the pull applied to the upper, and thereafter lasting the upper in the intervals between said locations by subjecting it to an overdrawing pull only and stapling it to the lip or shoulder of the sole.

64. That improvement in methods of lasting shoes which consists in pulling an upper at one portion of a shoe both heightwise of the last and inwardly over the sole and fastening it to the sole, and lasting the upper at a different portion of the shoe by subjecting it to an overdrawing pull only and fastening it.

65. That improvement in methods of lasting shoes which consists in subjecting an upper at one portion of the side of a shoe to an updrawing and an overdrawing pull and fastening it to the sole, and lasting successive portions of the upper in a different location along the side of the shoe by subjecting it to a series of overdrawing pulls only and fastening it.

66. That improvement in methods of making shoes of the type having a sole provided with an upper-attaching shoulder or lip, which consists in pulling inwardly over the sole simultaneously at the opposite sides of the shoe portions of the upper in locations where the edge of the sole curves inwardly toward the shank at the rear of the ball line and fastening the upper in said locations, and thereafter working inwardly and fastening to the lip or shoulder of the sole different portions of the upper successively along the sides of the shoe both forwardly and rearwardly of the ball line.

67. That improvement in methods of making shoes of the type having a sole provided with an upper-attaching shoulder or lip, which consists in pulling inwardly over the sole simultaneously at the opposite sides of the shoe portions of the upper in locations where the edge of the sole curves inwardly toward the shank at the rear of the ball line and fastening the upper in said locations, and thereafter operating on different portions of the upper successively along the sides of the shoe including portions in front of the ball line and in the shank to work the different portions inwardly and secure them to the sole by separate fastenings inserted into the lip or shoulder of the sole in directions extending inwardly along the plane of the sole.

68. That improvement in methods of making shoes of the type having a sole provided with an upper-attaching shoulder or lip, which consists in pulling inwardly over the sole simultaneously at the opposite sides of the shoe portions of the upper in locations where the edge of the sole curves inwardly toward the shank at the rear of the ball line and fastening the upper in said locations by tacks, and thereafter working different portions of the upper along the sides of the shoe successively inward over the sole and inserting staples to fasten them to the lip or shoulder of the sole.

69. A machine of the class described having, in combination, means for pulling an upper over a last, and means arranged to engage the upper initially at a substantial distance from the edge of the sole and movable in a direction at a substantial angle to the plane of the sole toward its bottom face to lay the upper inwardly over the sole with pressure substantially localized at a distance from the edge of the sole while the upper is held under tension by said upper pulling means.

70. A machine of the class described having, in combination, upper gripping means for pulling an upper over a last, and an overlaying member arranged to engage the upper initially and throughout its overlaying action in a location between said upper gripping means and the edge of the sole and spaced from said edge and to move in a direction in-

clined to the plane of the sole to force the upper into the angle between the margin and the lip or shoulder of the sole while the upper is held by said gripping means.

71. A machine of the class described having, in combination, a gripper for pulling an upper over a last, an overlaying member, a sole rest, means for moving said overlaying member relatively to the sole rest in a direction inclined to the plane of the sole toward the bottom face of the sole to tuck the upper into the angle between the margin and the lip or shoulder of the sole by pressure substantially localized at a distance from the edge of the shoe bottom, and controlling means for said gripper to cause it to maintain its grip on the upper during the inward movement of said overlaying member and thereafter to release the upper.

72. A machine of the class described having, in combination, a gripper for pulling an upper over a last, an overlaying member arranged to engage the tensioned marginal portion of the upper in a location spaced from the edge of the sole and to move in a direction inclined to the plane of the sole to tuck the upper into the angle between the margin and the lip or shoulder of the sole, means for fastening the upper in said angle, and controlling means for said gripper to cause it to maintain its hold on the upper until the upper is fastened.

73. A machine of the class described having, in combination, means for pulling an upper over a last, means for laying the upper inwardly over the margin of the sole, and means for driving a staple in a direction inclined to the plane of the sole to fasten the upper to the lip or shoulder of the sole.

74. A machine of the class described having, in combination, means for pulling an upper over a last, an overlaying member mounted for movement in a direction inclined to the plane of the sole to force the upper inwardly against the lip or shoulder of the sole, said member being constructed to provide a guideway for a fastening similarly inclined to the plane of the sole, and means for driving the fastening to fasten the upper to the lip or shoulder of the sole.

75. A machine of the class described having, in combination, means for pulling an upper over a last, means for laying the upper inwardly against the lip or shoulder of the sole by pressure directed at a substantial inclination to the plane of the sole, means for inserting a fastening in a direction similarly inclined to the plane of the sole to fasten the upper to said lip or shoulder, and means for clinching the fastening.

76. A machine of the class described having, in combination, a gripper and a sole rest relatively arranged for pulling the upper in a direction inclined outwardly from the edge of the sole, means for operating the gripper

after the upper has been thus pulled to draw the upper inwardly over the margin of the sole, and an overlaying member movable in a direction inclined to the plane of the sole for engaging the upper initially in a location spaced from the edge of the sole and for tucking it into the angle between the margin and the lip or shoulder of the sole.

77. A machine for lasting McKay shoes having insoles provided with channel lips comprising, in combination, a sole rest arranged to engage the insole in its channel and to position said lip in inclined relation to the plane of the insole, means for pulling the upper, and overlaying and fastening means arranged to force the upper inwardly against said lip and to insert a fastening into said lip at such an inclination to the plane of the insole as to position it in substantially perpendicular relation to the lip.

78. A machine for lasting McKay shoes having insoles provided with upper-attaching lips comprising, in combination, a sole rest arranged to engage the insole and to position said lip in inclined relation to the plane of the insole, means for pulling the upper, an overlaying member movable toward said lip in a direction inclined to the plane of the insole to lay the upper inwardly, and means for fastening the upper to said lip.

79. A machine for lasting McKay shoes having insoles provided with upper-attaching lips comprising, in combination, a shoe rest arranged to engage the insole and to position the lip in inclined relation to the plane of the insole, means for pulling the upper over the last, and means for laying the upper inwardly against said inclined lip by pressure applied in a direction substantially perpendicular to the lip and for driving a fastening in the same direction to secure it to said lip, the shoe rest being constructed to clinch the fastening.

80. A machine for lasting McKay shoes having insoles provided with upper-attaching lips comprising, in combination, a shoe rest arranged to engage the insole beneath said lip, means for pulling the upper over the last, an overlaying member arranged to engage the tensioned marginal portion of the upper in a location spaced substantially from the edge of the insole and movable inwardly toward said lip in a direction inclined to the plane of the insole, said member having a nose portion to press the upper against said lip and having also a guideway terminating in said nose portion for directing a fastening into the lip, and means for driving the fastening to secure the upper to the lip.

81. A machine of the class described having, in combination, means for pulling an upper over a last, and means for laying the upper inwardly over the sole, said upper pulling means being constructed to adjust the force of its pull on the upper to the action of

the overlaying means while continuing to hold the upper with an unslipping grip in the overlaying operation.

82. A machine of the class described having, in combination, a gripper for pulling an upper over a last, means for laying the upper inwardly over the sole, and controlling mechanism for said gripper automatically operative to adjust the force of the pull on the upper to the action of the overlaying means in the overlaying operation while continuing a firm grip on the upper.

83. A machine of the class described having, in combination, a gripper and operating means therefor comprising a spring through which to apply a yielding pull to the upper, means for laying the upper inwardly over the sole, and mechanism automatically operative to adjust the tension of said spring to the action of the overlaying means while the gripper continues its hold on the upper in the overlaying operation.

84. A machine of the class described having, in combination, a gripper for pulling an upper over a last, an overlaying member arranged to engage the tensioned margin of the upper in a location between said gripper and the edge of the sole and spaced substantially from said edge, said member being movable in a direction inclined to the plane of the sole to lay the upper inwardly, and automatic means for adjusting the force of the pull of the gripper on the upper to the action of the overlaying member before the overlaying operation is completed while maintaining the upper under control of the gripper.

85. A machine of the class described having, in combination, a gripper, a sole rest, operating means for effecting relative movement of said gripper and sole rest heightwise of the shoe for pulling the upper, additional operating means for effecting relative movement of said gripper and sole rest to draw the upper inwardly over the bottom of the last, and mechanism for throwing said first-named operating means out of operation without affecting the operation of said last-named operating means on the upper.

86. A machine for lasting different portions of a shoe successively, comprising a gripper and operating mechanism having an automatically determined cycle of movements to move the gripper first to pull the upper heightwise of the last and then to pull it inwardly over the bottom of the last, and means enabling the operator to change the cycle at will by eliminating said heightwise pull of the gripper without affecting its inward pull on the upper.

87. In a machine for progressively lasting shoes, a work rest for positioning a last and its shoe materials, a gripper for gripping the upper successively in different locations and for pulling it in each location over the last

and over the bottom of a sole on the last, an overlaying member arranged to engage each of the tensioned marginal portions of the upper initially in a location at a distance from the plane of the sole, and means for moving said overlaying member in a direction inclined toward the bottom face of the sole to lay the marginal portion of the upper upon said face by pressure substantially localized at a distance from the edge of the sole.

88. In a machine for progressively lasting shoes, a work rest for positioning a last and its shoe materials, a gripper for gripping the upper successively in different locations and for pulling it in each location over the last and over the bottom of a sole on the last, an overlaying member arranged to engage each of the tensioned marginal portions of the upper initially in a location at a substantial distance from the edge of the sole, means for moving said overlaying member in a direction at a substantial angle to the bottom face of the sole to lay the upper upon said face without any substantial wiping effect thereon, and means for causing the gripper to hold the upper under tension until the upper has been pressed against the sole by said overlaying member.

89. In a machine for progressively lasting shoes, a gripper for gripping and pulling an upper over a last successively in different locations, means for operating said gripper in each location to pull the upper in a direction inclined outwardly from the edge of a sole on the last and then inwardly over the sole, and an overlaying member arranged to engage the upper initially in a location spaced from the edge of the sole and movable in a direction inclined toward the bottom face of the sole to lay the upper over said face while it is held by the gripper.

90. In a machine for progressively lasting shoes, a work rest for positioning a last and its shoe materials, a gripper for gripping and pulling the upper successively in different locations, and an overlaying member for laying the upper inwardly over the bottom of a sole on the last in each of said locations, said overlaying member extending lengthwise in a direction inclined to the bottom of the shoe and being movable in the direction of its length to engage the upper with its end face in a location spaced from the plane of the sole and to bend the upper inwardly over the margin of the sole while the upper is held by the gripper.

91. A machine of the class described having, in combination, means for tensioning an upper over a last, mechanism for driving a staple to fasten the upper to a sole on the last, and means for forming a staple in a position out of the line of drive including a device for transferring it from forming position into position to be operated upon by the driving means.

92. A machine of the class described having, in combination, means for tensioning an upper over a last positioned bottom upward, a driver and means for operating it to drive a staple in a direction inclined to the bottom of the shoe to fasten the upper to a sole on the last, and means for forming a staple in a position above the path of movement of the driver and for moving it downwardly into the path of movement of the driver preparatory to the operation of the driver thereon. 70
93. A machine of the class described having, in combination, means for tensioning an upper over a last positioned bottom upward, means for driving a staple in a direction inclined to the bottom of the shoe to fasten the upper to a sole on the last, staple forming mechanism comprising an inside former located above the path of movement of the driving means and an outside former movable to form a staple over the inside former, and means for operating said outside former to carry the staple downwardly into the path of movement of the driving means. 80
94. A machine of the class described having, in combination, means for tensioning an upper over a last, and overlaying and fastening mechanism movable toward the shoe and including a member for engaging the tensioned upper and pressing it against a sole on the last and a member for driving a staple to fasten the upper to the sole, said overlaying and fastening mechanism including also means operative in response to the movement of said mechanism toward the shoe to form a staple in a position out of the path of movement of the driving member and operative thereafter to transfer the staple from forming position into the path of movement of said member. 90
95. A machine of the class described having, in combination, means for pulling an upper over a last having a sole thereon, and a device movable in a path inclined toward the outer face of the sole to engage the tensioned upper in a location spaced from the edge of the sole and, while maintaining engagement therewith confined substantially to that location, to bend the upper about said edge into contact with said face. 100
96. A machine of the class described having, in combination, a gripper for pulling an upper over a last having a sole thereon, and a device movable in a path at an angle to the outer face of the sole to engage the tensioned upper in a location between the gripper and the edge of the sole and to bend it about said edge into lasted position upon said face by pressure thus substantially localized at a distance from the edge of the shoe bottom. 110
97. A machine of the class described having, in combination, means for pulling an upper over a last having thereon a sole provided with a lip on its outer face, a work rest for engaging said lip and for clinching a fastening driven through the lip, a member movable toward said work rest in a path inclined toward the outer face of the sole to engage the tensioned upper in a location spaced from the edge of the sole and to bend the upper about said edge toward the plane of the sole and clamp it with the lip against the work rest, and means for driving a fastening from said member through the upper and the lip and against the work rest. 120
98. In a machine for progressively lasting shoes having soles provided with upper-attaching lips, a gripper for pulling different portions of an upper over a last successively in different locations along the edge of a shoe bottom, a work rest for engaging the lip of the sole to position the shoe and guide it in moving to different positions, a member movable toward said work rest in a path inclined toward the outer face of the sole to engage the tensioned upper at a distance from the edge of the sole and to bend it toward the plane of the sole into lasted position against the lip while it is held by the gripper, and means for fastening the upper to the lip. 130
99. In a machine for progressively lasting shoes having soles provided with upper-attaching lips, a gripper for pulling different portions of an upper over a last successively in different locations along the edge of a shoe bottom, a work rest for engaging the lip of the sole to position the shoe and guide it in moving to different positions, a staple-guiding nozzle movable toward said work rest in a path inclined toward the outer face of the sole to engage the tensioned upper with its end face at a distance from the edge of the sole and to bend the upper toward the plane of the sole into lasted position against the lip, and means for driving a staple from said nozzle through the upper and the lip and for clinching it against the work rest. 140
100. In a machine for progressively lasting shoes having soles provided with upper-attaching lips, a gripper for pulling different portions of an upper over a last successively in different locations along the edge of a shoe bottom, a work rest for engaging the lip of the sole to position the shoe and guide it in moving to different positions, a staple-guiding nozzle movable toward said work rest in a path inclined toward the outer face of the sole to engage the tensioned upper at a distance from the edge of the sole and to bend it toward the plane of the sole into lasted position against the lip, and means for driving a staple from said nozzle through the upper and the lip in a direction substantially parallel to the direction of the movement of the nozzle to incline the legs of the staple toward the base of the lip. 150

In testimony whereof I have signed my name to this specification.

GEORGE GODDU. 130
